The ornamental design for a cellular shade component, as shown and described.

DESCRIPTION

FIG. 1 is an isometric view of the front and left sides of a cellular shade component.

FIG. 2 is a left side elevation view of the cellular shade component of FIG. 1.

FIG. 3 is a front elevation view of the cellular shade component of FIG. 1. The rear elevation view is a mirror image thereof; and,

FIG. 4 is top plan view of the cellular shade component of FIG. 1. The bottom plan view is a mirror image thereof. The dot-dash-dot broken lines visible in FIGS. 1 and 4 represent the boundaries of the claim and form no part thereof. The dash-dash broken lines in FIGS. 1-4 represent portions of the cellular shade component that form no part of the claimed design.
